UNITED STATES PATENT OFFICE.

CHARLES S. BURTON, OF OAK PARK, ILLINOIS, ASSIGNOR TO EMIL TYDEN, OF HASTINGS, MICHIGAN.

PEDESTAL-EXTENSION-TABLE LOCK.

No. 892,131.

Specification of Letters Patent.

Patented June 30, 1908.

Application filed July 1, 1907. Serial No. 381,710.

To all whom it may concern:

Be it known that I, CHARLES S. BURTON, a citizen of the United States, residing at Oak Park, in the county of Cook and State of Illinois, have invented new and useful Improvements in Pedestal-Extension-Table Locks, of which the following is a specification, reference being had to the drawings forming a part thereof.

10 The purpose of this invention is to provide an improved device for locking together the parts of a pedestal extension table, particularly adapted for such use in a table in which the table top members have a limited range 15 of extensibility without opening the pedestal.

It consists of the features of construction shown and described, as indicated in the claims:—

In the drawings:—Figure 1 is a vertical 20 longitudinal section of a pedestal extension table containing this invention, the parts being shown at locked position of both top and pedestal. Fig. 2 is a similar view of the middle portion of such table showing the top extended to a degree not causing the pedestal to be unlocked. Fig. 3 is a detail inverted 25 plan view showing a locking device which may be employed to connect the table top members. Fig. 4 is an inverted detail plan 30 view of certain parts which are mounted on the under side of the table top. Fig. 5 is a detail section of the pedestal in the same plane as Fig. 2 showing a modification of the latching device.

35 The two table top members, 1 and 2, it may be understood, are extensible relatively to their respective pedestal members, 3 and 4, by means of the usual construction for this purpose. The device for locking the 40 pedestal members together comprises a bell-crank lever, 5—6, fulcrumed upon one pedestal member, the lever having connected to its arm, 6, a latch, 7, which engages a suitable 45 coöperating element, as a staple, 8, on the opposite pedestal member. To the other arm, 5, of the bell-crank lever there is connected a link, 9, which extends upward to the top of the pedestal where it is connected to the arm, 10, of the bell crank lever, 10—11, 50 whose arm, 11, in the position in which it is normally held by the spring, 17, acting against the stop, 9^a, on the link, 9, extends upward and stands in the path of movement of two abutments, on the table top member, 1, formed

respectively by the edge of the plate, 12, and 55 the part, 13, pivoted to it, as seen in Fig. 2. The abutment, 12, is in such position on the under side of said table top member as to encounter the arm, 11, in the closing movement of said table top member at any desired 60 point within the range of the movement of said top member from the position at which it is extended for receiving a single filler to closed position of the table top member 65 relatively to the pedestal member. Assuming nine inches as the width of a filler, the range of movement of the table top member, 1, which may be made available for actuating the lever arm, 11, is four and a half inches. The relative lengths of the different arms of 70 the bell-crank levers, 10—11 and 5—6, may be such as to cause the movement of the table top member after the edge of the plate, 12, encounters the arm, 11, until said table top member is at closed position to give 75 any desired amount of drawing movement to the latch, 7. I preferably proportion these parts so that about two and one-half inches of movement of the table top member will give one inch drawing movement to the latch. 80 One-half of this amount of action on the pedestal will ordinarily be adequate, and the parts may accordingly be proportioned for less when the space in the pedestal is too limited for the amount indicated. 85

I locate the latch, 7, and staple, 8, relatively so that they may become engaged while the pedestal members are one inch apart or whatever distance the latch is arranged to draw in the closing movement of 90 the top. The gap in the pedestal will then be closed up by the movement of the table member through two and one-half inches of its closing movement relatively to its pedestal member, 3. It will be seen that the rocking of the lever arm, 11, inward, thrusting the link, 9, downward, causes the arm, 6, of the bell-crank lever, 5—6, to pull the latch, 7, toward the pedestal member, 3, and thus draw the two pedestal members together. 95 Any convenient means may be provided, if desired, for securing the table top members, 1 and 2, together when they are thus closed; in case the construction of the parts is such that some springing of the pedestal member 100 relative to the table top might be necessary to cause the top to be closed snugly after the pedestal members come into contact, it is 105

desirable to have the devices for connecting the table top members adapted to draw them slightly or clamp them together; and for that purpose, any familiar engaging device 5 adapted for such clamping action may be employed, as, for example, any of the familiar types of sash locks, of which two elements may become engaged while there is slight separation between the parts which they connect which are closed up in completing the engagement. I have shown such a familiar type of lock comprising two parts, 14 and 15, mounted on the under side of the two table members respectively just outside the slides 10 in position to be reached by the operator, but out of sight. Any mechanic will readily apply other similarly operating expedients for connecting the table top members and so causing them to hold the pedestal members 15 tightly together through the devices described.

A table of this type may be constructed so that the pedestal shall not be unlocked automatically unless the top is to be extended so 20 as to receive more than a determined number of fillers. In the construction shown, it is assumed that a table is designed to be used with one filler inserted without extending the pedestal. Whenever the pedestal is to 25 be extended the top members will be extended more than the amount necessary for 30 accommodating this pre-determined number—as in the drawings, one filler. And for 35 unlocking the pedestal when the top is extended beyond this pre-determined limit there is provided the abutment, 13, carried by the 40 table member, 1, which encounters the arm, 11, of the bell crank lever, 10—11, in the extending movement of said table-top member, 1, and rocks the lever for operating the pedestal lock to disengage the latch, 7, from the 45 staple, 8, which, it will be understood, is effected by first causing the lever, 5—6, to swing its arm, 6, inward to the extent of the draw provided for; and when that limit is 50 reached the back stop, 7^a, of the latch strikes the back edge of the lever arm, 6, and the further rocking of the lever, 10—11, causes the latch to be carried with the lever, 5—6, 55 in the upward swinging movement of the arm, 6, disengaging it from the staple and permitting the pedestal members to be spread. The further extending movement of the table member, 1, carries the abutment, 13, 60 clear of the lever arm, 11, leaving the lever, 10—11, free to return to its normal position to which the weight of the latch, 7, and link, 9, will cause it to return, and where it is stopped, as described, by the spring, 17, holding the latch, 7, with slope nose in position for 65 encountering the staple and engaging it when the pedestal members are pushed together. To receive the encounter of the abutment, 13, the lever arm, 11, may have a sideward 70 jutting stud, 11^a, and the abutment, 13, is

preferably carried, as shown, at the end of an arm, 12^b, of the plate, 12, through which the stop pin, 12^a, is inserted to limit the swinging in one direction of the abutment, 13, as hereinafter explained. The reason for 70 thus projecting the abutment, 13, from the edge of the table top member by which it is carried is to position said abutment properly for encountering the lever arm, 11, only after the table top member, 1, is withdrawn from 75 the parting plane a proper distance for admitting one filler when the other table top member is similarly withdrawn. The abutment, 13, is pivotally mounted on the arm, 12^b, stopped by the pin, 12^a, against swinging 80 toward the opposite table member, but free to swing back toward the member, 1, which carries it; and when said table top member, 1, is moved inward for closing up the table the abutment, 13, swings at its 85 pivotal connection to ride back over the stud, 11^a, resuming its pendent position by gravity when it has passed the stud. It will be seen that the pedestal lock may be operated for 90 unlocking without the provision for its automatic actuation by the table top member, 1, because, the top of the table being open, the pedestal-lock operating devices above the pedestal are accessible, and in some instances it may be preferred to omit the automatic 95 unlocking device.

In Fig. 5 there is shown a modification of a pedestal locking device in which the bell-crank lever, 5—6, does not carry a latch, but, instead, a latch, 7^x, is carried by the opposite 100 pedestal member and engages the offset or wrist, 5^x, on the arm, 6, of the bell-crank lever. The operation of the device will be 105 obviously the same as that of the form shown in Fig. 1.

If desired, there may be combined with the devices already shown and described for causing the closing of the top to draw together and lock the pedestal parts, means for causing the member, 1, of the table top 110 which operates the pedestal lock to become locked automatically in the same closing process by which it locks the pedestal. A simple expedient for this purpose consists in making the abutment, 12^a, on the table top 115 member, 1, which encounters the arm, 11, of the bell-crank lever, 10—11, with a serrated lower face, 12^c, and providing the arm, 11, at the portion of its upper end which rides under the plate correspondingly serrated, so that such two serrated members 120 will be engaged as the lever rides under the plate, the inward inclination of the lever in this action causing it to act as a detent pawl preventing the rotation or outward withdrawal of the table top carrying the plate when it has once been pushed in so that the plate is thus engaged with the lever.

In order to disengage the table top member, 1, from the lever, 11, as will be necessary 130

in order to spread the table top, the plate, 12, which carries the serrated abutment, 12^a, is mounted slidably on the under side of the table top member, 1, being extended off above the extension slides and provided with a hooked end, 12^d, which may be reached just inside the margin of the table for moving it in the direction of the serrations so as to disengage the serrated face from the end of the lever arm, 11; leaving said lever arm to ride upon the smooth track, 12^e, alongside the serrated face, 12^c. If it is preferred not to lock the top in this manner, the plate, 12, may be left at all times pushed inward so that the lever 11, will ride on the smooth track, 12^e, and in order that the abutment, 13, may operate with equal efficiency in either case, the stud, 11^a, is duplicated upon both sides of said lever arm, 11, being preferably formed by a pin set through the arm projecting at both sides.

I claim:—

1. In a pedestal extension table, having the table top members extensible relatively to their respective pedestal members, in combination with such table top and pedestal members; coöperating pedestal locking devices mounted on the two opposite pedestal members and located at a substantial distance below the top of the pedestal; coöperating devices mounted respectively at the top of one pedestal member and on the table top member pertaining thereto, adapted to be engaged in the closing movement of the table top member with respect to the pedestal member for resisting the retraction or opening movement of said table top member, and operating connections from said devices at the top of the pedestal to one of said coöperating devices for connecting the pedestal members, adapted to hold said last mentioned device in pedestal-locking position when the table top member is in closed position.

2. In a pedestal extension table having the table top members extensible relatively to their respective pedestal members, in combination with such table top and pedestal members, coöperating pedestal locking devices mounted respectively on the two opposite pedestal members at a substantial distance below the top of the pedestal; coöperating devices, one mounted at the top of one pedestal member and the other on the table top member pertaining thereto, adapted to become engaged in the closing movement of the table top member with respect to said pedestal member, and by their engagement to resist the opening or retracting of the table top member, and operating connections from the said device at the top of the pedestal to one of the said coöperating pedestal locking devices for holding the latter in pedestal locking position while said coöperating devices on the table top and pedestal respectively are so engaged

and means for securing together the two table top members.

3. In a pedestal extension table having the table top members extensible relatively to their respective pedestal members, in combination with such table top and pedestal members; a vertically positioned element on one pedestal member; coöperating devices for engaging each other, one operatively connected with said vertically positioned element and the other carried by the opposite pedestal member located at a substantial distance below the top of the pedestal; means on one table-top member for actuating said vertically positioned element above the pedestal for pedestal-closing in the closing movement of the table-top member, the mutually encountering elements on the pedestal and table top respectively being relatively constructed for detaining-pawl-and-ratchet action in said closing movement to lock the table-top member at closed position when the pedestal has been closed by said movement, and means for disengaging said elements at will.

4. In a pedestal extension table having table top members extensible relatively to their respective pedestal members, in combination with such table top and pedestal members, a vertically positioned element on one pedestal member; coöperating devices for engaging each other operatively connected with said vertically positioned element and the other carried by the opposite pedestal member, located at a substantial distance below the top of the pedestal; a lever at the top of the pedestal connected with said vertically positioned element for operating it, and an abutment on one table top member positioned for encountering said lever in the closing movement of the table top and actuating said lever for pedestal-closing movement of said engaging devices, said abutment and lever being relatively positioned and formed to permit the abutment to run on the end of the lever for encountering and rocking it, said lever end and the face of the abutment which runs on it being adapted for engagement to resist reverse travel of the abutment over the lever end.

5. In a pedestal extension table having table top members extensible relatively to their respective pedestal members, in combination with such table top and pedestal members, pedestal locking devices mounted on the two opposite pedestal members respectively at a substantial distance below the top of the pedestal; coöperating devices mounted one at the top of one pedestal member and the other on the table top member pertaining thereto, constructed for engagement with each other in the closing movement of the table top member with respect to the pedestal member for resisting extension or retraction of said table top

14
member; operating connections from the said device mounted at the top of the pedestal member to one of the pedestal locking devices, for holding it in locking position when the table top member is closed, the device on said table top member being movable transversely with respect to the direction of extending and closing movement of a table top member for disengagement from the

coöperating device at the top of the pedestal member.

In testimony whereof, I have hereunto set my hand at Chicago, Illinois, this 24th day of June, A. D., 1907.
